(57) **CLAIM**

The ornamental design for apparel sleeve ends, as shown and described.

DESCRIPTION

FIG. 1 is a front view of apparel sleeve ends showing my new design;

FIG. 2 is an enlarged outside side view of the sleeve ends;

FIG. 3 is an enlarged inside side view of the sleeve ends;

FIG. 4 is an enlarged front view thereof;

FIG. 5 shows a view similar to the view of FIG. 2, but with the ears of the left-hand image pivoted upwardly; and,

FIG. 6 shows a bottom view of my claimed design.

The broken lines in FIGS. 1-5 represent the portions of the shirt, which form no part of the claimed design.
